UNITED STATES PATENT OFFICE.

HIRAM B. HARDING, OF LOS ANGELES, CALIFORNIA.

TUG SHEAVE-CLUTCH.

SPECIFICATION forming part of Letters Patent No. 707,321, dated August 19, 1902.

Application filed October 19, 1901. Serial No. 79,230. (No model.)

To all whom it may concern:

Be it known that I, HIRAM B. HARDING, a citizen of the United States, residing at Los Angeles, in the county of Los Angeles and 5 State of California, have invented a new and useful Tug Sheave-Clutch, of which the following is a specification.

This invention relates generally to drill-rig appliances, and more particularly to a sheave-clutch for a tug-rope pulley, the objects of 10 the invention being to secure perfect control of the tools while they are being raised and lowered, to save the time of placing the tug-rope on the bull-wheel when it is desired to 15 pull the tools, and also to save the time of removing the said rope when the bull-wheel is not in use.

Another object of the invention is to provide a device which will prevent the wear 20 upon the tug-rope which occurs in the present form of rig by the rope remaining upon the tug-sheave while the rig is in action.

With these objects in view the invention 25 consists in the novel features of construction and combination hereinafter fully described, and pointed out in the claims.

In the drawings forming a part of this specification, Figure 1 is an enlarged view showing 30 in elevation a portion of the band-wheel and tug-rope sheave. Fig. 2 is a sectional view of the band-wheel, tug-sheave, and the clutch mechanism, the shaft and the operating-lever being shown in plan. Fig. 3 is a perspective view showing a portion of the tug-sheave.

35 Fig. 4 is a view showing a portion of the band-wheel and clutch-section. Fig. 5 is a detail view illustrating the manner of connecting the sheave-spokes to the rim, the spokes being shown in dotted lines; and Fig. 6 is a section taken on the line 8 8 of Fig. 4.

In carrying out my invention I make no change whatever in the general construction of the rig; but to the inner face of the band-wheel A, I securely fasten a circular toothed 45 rim B, said rim being securely bolted to a spacing-rig C, attached to the face of the band-wheel, and in practice I prefer to employ a reinforcing-plate C' upon the opposite face of the band-wheel, and I also prefer to 50 employ the central reinforcing and bearing plates C². The band-wheel is mounted upon the shaft D, and loosely mounted upon this

shaft and sliding thereon is the tug-rope sheave E, carrying the tug-rope. The tug-sheave E comprises a circumferentially-grooved rim E', the radial spokes or arms E², and the hub E³. The inner face of the rim E' has clutch-teeth E⁴ formed thereon at regular intervals, said teeth being preferably arranged in radial alinement with the inwardly-projecting ears or lugs E⁵, to which the outer ends of the spokes are secured, parallel flanges E⁶ connecting the said ears or lugs E⁵ with the rim E', thereby providing sockets into which the outer ends of the spokes 65 fit, and by referring to Fig. 4 it will be noted that the outer side of the rim E' is beveled or cut away, as shown at E⁷, and that the outer ends of the spokes are shouldered, as shown at E⁸, in order to embrace the inner 70 edge of the rim snugly.

The hub E³ is formed with a broad collar E⁹, to which the inner ends of the spokes are attached, a circular ring or plate E¹⁰ being arranged upon the opposite side and through 75 which the bolts are passed, thereby securely clamping the spokes between the collar E⁹ and circular plate or ring E¹⁰. The outer end of the hub is formed with a circumferential groove, in which fits the bifurcated end I of 80 the shifting-lever I', said lever being fulcrumed upon the upper end of a post K, carrying a pin K', a strap K² being secured to the side of the lever for the purpose of embracing the said pin, thereby securely pivot- 85 ing the lever upon the end of the post. The lever I' extends to a point where it is within easy reach of the operator, and by shifting the lever the tug-sheave can be thrown toward the band-wheel, and the moment the 90 clutch-teeth E⁴ engage the toothed rim B the tug-sheave will virtually become a part of the band-wheel and will move in unison therewith, and consequently operate the tug-rope, which in turn will operate the bull-wheel. 95 When it is desired to check the operation of the bull-wheel, the rope or lever is reversed, drawing the tug-sheave away from the band-wheel, and it will thus quickly come to a state of rest, while the band-wheel is permitted to 100 rotate without operating the rug-rope or the bull-wheel.

It will thus be seen that I provide a very simple but highly efficient device which can

be applied to any of the rigs now in use and by means of which the operator can have perfect control of the tools at all times, and it will be noted that I entirely avoid the necessity of removing and replacing the bull-rope, and it will also be noted that I also avoid all unnecessary wear upon the tug-rope. The tug-sheave although extremely light in construction is also built up in a manner insuring its durability.

Having thus fully described my invention, what I claim as new, and desire to secure by Letters Patent of the United States, is—

1. A tug-sheave comprising in combination a rim having a circumferential groove and provided with clutch-teeth at regular intervals, said rim having sockets, the spokes having their outer ends secured in said sockets the hub to which the inner ends of said spokes are attached, said hub having a circumferential groove, a shifting-lever adapted to fit

said groove and the band-wheel provided with clutch-teeth, substantially as described.

2. A tug-sheave comprising in combination a rim having a circumferential groove and provided with clutch-teeth upon the inner face of said rim at regular intervals, the inwardly-projecting ears or lugs integral with the rim and in alinement with the clutch-teeth, the parallel flanges connecting the rim and ears or lugs thereby providing sockets, the spokes shouldered at their outer ends and fitting into the said sockets and embracing the edge of the rim, the hub formed with a collar to which the inner ends of the spokes are secured, and the band-wheel provided with clutch-teeth, substantially as shown and described.

HIRAM B. HARDING.
